UNITED STATES PATENT OFFICE.

JOSEF SCHIESSLER, OF BADEN, NEAR VIENNA, AUSTRIA-HUNGARY.

RECEIVING APPARATUS FOR ALTERNATIVE WIRELESS TELEGRAPHY AND TELEPHONY.

1,092,294.

Specification of Letters Patent.

Patented Apr. 7, 1914.

Original application filed April 20, 1908, Serial No. 428,255. Divided and this application filed August 11, 1910. Serial No. 576,742.

To all whom it may concern:

Be it known that I, JOSEF SCHIESSLER, subject of the Emperor of Austria-Hungary, residing at Baden, near Vienna, Austria-Hungary, have invented certain new and useful Improvements in Receiving Apparatus for Alternative Wireless Telegraphy and Telephony, (being a division of my application, Serial No. 428,255, filed April 20, 1908,) of which the following is a specification.

My invention relates to wireless apparatus for receiving telephonic or telegraphic signals and has for its object a novel arrangement and construction of parts designed to transmit electric waves or oscillations, which are picked up by means of a double antenna system and are determined in respect to their direction, to a strong current circuit including incandescence resistances, for the purpose of strengthening thereby the amplitude of the oscillations and also the action of the same which action otherwise would be weak.

Referring to the drawings in which like parts are similarly designated: Figure 1 is a perspective view of one of the adjustable condensers in connection with my system. Fig. 2 is a diagrammatic view of the electrical circuits, and apparatus at a wireless station. Figs. 3 and 4 are diagrams of modifications of certain elements. Fig. 5 is an elevation, partly in section and Fig. 6 is a plan, of a mount for one of the conical solenoids or windings used in connection with my system.

The apparatus constructed according to my invention consists of the following parts: 1. The antenna system provided with a calling device. 2. The proper receiving apparatus. The latter apparatus is divided up into two parts *i. e.* (a) apparatus for receiving telegraphic messages, and (b) apparatus for the reception of telephonic messages.

45 *The antenna system.*—The antenna system is arranged to be connected with the receiving apparatus and consists of two plate condensers 1 and 2, of the form hereinafter described, each of which contains five plates. 50 The inner even numbered plates 3 and 4 with the same sign are connected by means of conducting rods 5, 6 to rollers 7, 8 respectively which are slidably mounted upon the said rods and make contact with the an-

tenna wires 9, 10 wound in the form of two coils and constructed in the form of the well known Lecher system, and which have the length of half a wave and are connected at the nodal points of the tension, by a metallic bridge 11, which is itself grounded by a wire 12. The lower outer coatings 13, 14 of the condensers are connected to the proper receiving apparatus the connection of which will be hereinafter described. In using the double antenna in the manner of a Lecher system, moreover, the purpose was aimed at to determine with the aid of a revolving double antenna system the direction of the incoming electric waves just in the same way as is the case with similar receiving antenna arrangements and as was proved as being possible by several pioneers in the art referred to. With this object in view the wires 9, 10 are wound on two masts 9', 10', respectively, which are hinged at 15 to a revoluble platform 16, so that the two masts 9' 10' can be rocked, if necessary, about the hinges 15 and the whole antenna system be turned into a position which will be suitable for the reception of the incoming waves propagated in the predetermined direction. Hinged masts have heretofore been used, see J. Zenneck, "Leitfaden der Drahtlosen Telegraphie" 1909, page 317 *et seq.* Published by Ferdinand Enke, at Stuttgart, Germany. In addition to the said arrangement the double antenna system being used as receiving apparatus is built up as a completely closed oscillating circuit by connecting the upper outer coatings 17, 18 of the condensers with each other by means of a conductor 19. On the other hand a calling device is connected with the antenna system. For the purpose of connecting the said calling device a sensitive relay 20 is bridged with a switch 21 across the two antenna coils at the center points of the same, where an oscillation loop is being formed and in the circuit of the relay contacts is arranged any suitable simple or combined signaling device 22 of known kind.

Receiving apparatus.—The supply current circuit including a source of current *o* is divided at 23 and provides current for either receiving telegraphic signals or for receiving telephonic messages. In the first case the supply current traverses a regulating resistance 24 and two conical chok-

ing coils 25, 26 up to the switch contact 27. If the three pole lever switch 28 be in the position shown, in engagement with the contacts 29, 30, the circuit is closed across 27, 31. This circuit includes a double cone-shaped solenoid 32 which consists of a wire of high resistance and good heat conductivity, and from which two wires lead off current to the contacts 33, 34. By the switch 10 lever 28 an oscillating circuit is however closed in which are placed cone shaped transformer solenoids 35, 36 over the conductor 37 and parallel therewith is a variable condenser 38. If, however, the switch 15 lever 28 be moved over into engagement with the contacts 39, 40, another part of the principal current circuit passes through a regulating resistance 41, receiving solenoids 42, 44 and a junction piece 43 to the contact 45. In a shunt circuit branching off from the junction piece 44 is a condenser 46, to the inner coatings of which a telephone 47 is connected. The undulatory circuit (electric waves superposed on the continuous current) will alternately load and unload the condenser 46. Moving the switch lever 28 over into engagement with contacts 39, 40, causes the closing of the telephone receiving oscillating circuit including a 20 variable condenser 48. From the oscillating circuit, branching off on either side of the condenser 48, is a shunt circuit including a double cone shaped solenoid 49 the resistance of which is very small.

30 Instead of the resistance coil 32 of the telegraphic receiving apparatus and of the freely conducting solenoid 49 of the telephonic receiving apparatus, an incandescent lamp, 50, see Fig. 3, may be inserted, the solenoid-like wound filament of which produces a magnetic field which is influenced by two cone-shaped solenoids 51, 52 of the oscillating circuit. In the telephonic receiving apparatus the incandescent lamp 45 50 would be placed in the circuit with the supply wires 53, 54, while the oscillating circuit, traversed by the electrical waves, would include the two solenoids 51, 52 instead of the original double cone-shaped 50 solenoid 49. The arrangement shown in Fig. 4 may, however, be used, in which in the telegraphic receiving apparatus two incandescent lamps 55, 56 are placed in the principal circuit, while instead of the two cone-shaped solenoids 35, 36, of the oscillating circuit, a single double cone-shaped solenoid 57 is employed, see Fig. 4. Such an arrangement may, however, be also used in the telephonic receiving apparatus, the two 60 incandescent lamps 55, 56, Fig. 4, being substituted for the two cone-shaped solenoids 42, 43. The incandescent lamps might however be just as well replaced by a Tyndall's platinum lamp, which would allow current 65 of greater strength to be used. In such an

arrangement the fluctuations in the intensity of the light of the incandescent lamp could be utilized to influence a light sensitive film.

In a system of wireless telegraphy and telephony as great an operating range as possible is to be attained, and it should therefore be sought to give the receiving apparatus as great a capacity as possible and very small self induction. This is accomplished by the use of condensers which simultaneously bring about the coupling of the oscillating circuit. In decreasing self induction however the coupling co-efficient becomes smaller and smaller although it must increase with increasing energy in order to render a powerful induction possible. This is effected according to this invention by the peculiar construction and peculiar use of condensers which comprise sliding parts as hereinafter described. Fig. 1 of the accompanying drawing illustrates a condenser of this kind. Upon a base plate *a* and upon a plate *b* that is mounted to slide thereon are arranged six or more plates. The two outer plates *c* are secured to a base board *g*, while upon the slide *b* are arranged alongside each other the four inner plates *d* at equal distances apart and which can be pushed as far as desired between the two previously mentioned plates *c*, whereby the capacity of the condenser can be regulated within any desired limits. The four inner plates *d* are, however, so connected up that the even and odd plates, respectively are always connected with each other, see Fig. 2 100 since these have the same sign. By this means the coupling co-efficient increases without the self induction increasing at the same time. The air is used as a di-electric, and its di-electric constant can be increased 105 by a permanent or electro-magnet placed over the gaps between the plates and by means whereof the lines of induction, which pass over from one plate to another, are deflected or blown away, as are the sparks in 110 the magnetic spark extinction. The condenser plates are placed in a strong magnetic field established between the poles of an electro-magnet or permanent magnet. By the action of the said field the lines of force 115 will deflect the lines of electric induction between the condenser plates generated by the charge and discharge of the condenser and similar to the well known action of magnetic spark extinction, said lines of induction will be "blown off." Consequently the 120 sparking voltage will increase, and thus an effect is obtained similar to that of inserting a medium of a higher dielectric constant between the condenser plates. This form of condenser obtains throughout the whole apparatus. In like manner, that is to say, throughout the whole apparatus, the form 125 of a single or double cone is given to all the solenoids, whereby a concentration of 130

the magnetic lines of force and thereby a more powerful action is obtained. In this way it is possible, so to speak, to produce bi-convex and bi-concave lenses for magnetic rays of force and to collect them into a focus, the entire magnetic field being accordingly concentrated into one point, and thereby uncommonly increasing the action.

If a telegraphic message is to be received the switch lever 28 is placed as above stated in engagement with the contacts 29, 30, 27. The electric pulsating currents coming in from the antennae 9, 10 traverse the oscillating circuit 29, 30, 35, 36 and, strengthened by the condenser 38 connected in parallel, influence the magnetic field of the cone-shaped solenoids 35, 36 in such a way that its fluctuations so influence the constant magnetic field of the double cone-shaped solenoid 32 which is traversed by the principal current, that the current flowing therethrough pulsates in the rhythm of the interruptions of the Morse key of the transmitting instrument. This pulsating current may directly operate a tapper 4 or a writing apparatus, or other similar device, which may be connected to the contacts 33, 34. If, however, the apparatus be modified according to Fig. 3, the fluctuating intensity of the light of the incandescent lamp, a platinum filament lamp, for example, may be utilized to photograph the fluctuations upon a moving light sensitive screen or film, these fluctuations being analogous to the dashes and dots of the Morse alphabet. The same result might also be attained, with suitable modifications, with the apparatus shown in Fig. 4. If, however, the switch lever 28 be placed into engagement with the contacts 31, 39, 40, the oscillating circuit 39, 40, 48, will be switched in together with its shunt connected solenoid 49, and the principal circuit will be closed as well. The receiving apparatus is then switched in for telephony. The incoming waves pass through the oscillating circuit 39, 40, 48, and the double cone-shaped solenoid 49 connected in shunt, and the magnetic field of such solenoid begins to fluctuate through the oscillations and the speech oscillations superposed upon them in the rhythm of these latter. These oscillations strengthened by the simultaneous charges and discharges of the condenser 48, influence in their turn the constant magnetic field of the solenoids 42, 43 which are traversed by the constant supply current. This constant supply current is properly regulated by the resistance 41 and the field of the solenoids 42, 43 is so influenced by the oscillations that the variable condenser 46 connected in shunt is charged and discharged in the same rhythm, the fluctuating capacities derived from the inside plates, which are charged by induction from the outer ones, influencing the telephone 47 in

the rhythm of the emitted superposed speech oscillations. The same thing will also happen if two incandescent lamps 55, 56, be placed in circuit as shown in Fig. 4, instead of the two solenoids, 42 and 43. The apparatus shown in Fig. 3 works in the same way also, the double cone-shaped solenoid 49 being replaced by the two cone-shaped solenoids 51, 52 and the cone-shaped solenoids 42, 43 of the principal circuit together with their connecting piece 44 being replaced by the incandescent lamp 50, whose coiled filaments act as resonating windings.

Instead of ordinary platinum filament incandescent lamps being employed, lamps having platinum spirals in a glass globe from which the air has not been withdrawn may be used with advantage.

The magnetic field of the cone-shaped solenoids, which, owing to the conical form of the said solenoids, is concentrated at one end of each solenoid, can be strengthened or weakened or made as effective as may be desired by mounting each of the two solenoids (35, 36 or 42, 43) to rotate upon a disk 58 (Figs. 5, 6), the two disks being movably mounted upon a sliding base 59 capable of sliding between fixed guides 60. The disk 58 with the coil supported upon it is held in its rotated adjusted position by a thumb screw 61.

Claim:

1. In a wireless signaling system, a receiver comprising a supply circuit containing a resistance element, antennae, a circuit connected thereto containing a winding positioned to magnetically influence said resistance, a condenser in parallel with the resistance and a receiving instrument connected in parallel to said resistance.

2. In a wireless signaling system, a receiver comprising a supply circuit containing a resistance element heated to incandescence by continuous current, antennae, a circuit connected thereto containing a winding positioned to magnetically influence said resistance, a condenser in parallel with the resistance and a receiving instrument connected in parallel with said resistance.

3. In a wireless signaling system, a receiver comprising a supply circuit containing a resistance element, antennae, a circuit connected thereto containing a winding positioned to magnetically influence said resistance, an adjustable condenser in parallel with the resistance and a receiving instrument connected in parallel with said resistance.

4. In a wireless signaling system, a receiver comprising a supply circuit containing a resistance element heated to incandescence by continuous current, antennae, a circuit connected thereto containing a winding positioned to magnetically influence said resistance, an adjustable condenser in parallel

with the resistance and a receiving instrument connected in parallel with said resistance.

5. In a wireless signaling system, a receiver comprising a supply circuit having a resistance winding therein heated by continuous current, antennæ, a circuit connected thereto containing a winding adjustable with relation to the resistance to vary the action of the magnetic field of said winding on the resistance, a condenser in parallel with the winding and a receiving instrument in parallel with the heated winding.

6. In a wireless signaling system, a receiver comprising a supply circuit having a double helical heated winding therein, antennæ, a circuit connected thereto containing two conical windings positioned to act at the ends of the heated winding, means to adjust said two conical windings, an adjustable condenser in parallel with said two windings, and a receiving instrument connected in parallel with the heated winding.

7. In a wireless signaling system, a receiving circuit supplied by continuous electric current, a telegraphic receiving circuit forming a branch thereof and including a double helical winding, an oscillating circuit having capacity and including conical windings adjacent the aforementioned winding.

8. In a wireless signaling system, a main receiving circuit supplied with continuous current electricity, a receiving telephone circuit arranged to be connected thereto and including windings also in said main circuit and an adjustable condenser, a telephone receiver connected to the condenser, an oscillating circuit having capacity and a winding in proximity to the aforesaid windings.

9. In a wireless signaling system, a main receiving circuit supplied with continuous current electricity, a receiving telephone circuit arranged to be connected thereto and including a pair of windings in series and also in said main circuit, an adjustable condenser connected in parallel with said windings, a receiving oscillating circuit, a double conical winding therein in proximity to the windings and a condenser in parallel with the double conical winding.

10. In a wireless signaling system, a main receiving circuit supplied with continuous current electricity, a receiving telephone circuit arranged to be connected thereto and including a pair of windings in series also included in said main circuit, and of high resistance, an adjustable condenser connected in parallel with said windings, a receiving oscillating circuit, a double conical wind-

ing therein in proximity to the windings, and a condenser in parallel with the double conical winding.

11. In a wireless signaling system, a main receiving circuit supplied with continuous current electricity, a receiving telephone circuit arranged to be connected thereto and having a winding also included in said main circuit, an oscillating circuit having an oscillating winding adjacent the said winding, a receiving telegraph circuit having a winding, an oscillating circuit pertaining thereto including an oscillating winding, antennæ, and means to connect either of said oscillating circuits to the antennæ and simultaneously connect their pertaining circuits to the receiving circuit.

12. In a wireless signaling system, a source of direct current, a telegraph receiving circuit and a telephone receiving circuit, regulable resistances between the current source and each of said circuits, a resistance for each circuit, a resonating circuit for each receiving circuit including windings positioned to magnetically influence the resistances in the circuits and a condenser in each resonating circuit in parallel with the winding therein, antennæ, and switches to connect the antennæ with either receiving and resonating circuit.

13. In a wireless signaling system, antennæ comprising masts having windings thereon of about half a wave length, a metallic bridge connecting the windings and grounded, a condenser for each mast winding and means to adjustably connect the condensers to their respective windings, said condensers connected together in parallel, a plurality of receiving oscillating circuits and means to connect the condensers to any of said circuits.

14. In a wireless signaling system, antennæ comprising a rotatable platform, two masts hinged thereto, windings on the masts substantially half a wave in length, a metallic bridge connecting said windings and grounded at its center, a condenser for each mast, means to adjustably connect each condenser to its pertaining winding, said condensers connected in parallel and two receiving oscillating circuits and means to connect the condensers to either of said circuits.

In testimony whereof I have hereunto set my hand in presence of two subscribing witnesses.

JOSEF SCHISSLER.
